(57) **CLAIM**

We claim the ornamental design for a kite, as shown and described.

DESCRIPTION

FIG. 1 is a perspective view of the kite design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side being a mirror image thereof.

The portion shown in broken lines in FIGS. 1 and 4 is for illustrative purposes only and forms no part of the claimed design.
